(57) **CLAIM**

I claim the ornamental design for an insole, as shown and
described.

DESCRIPTION

FIG. 1 is a top perspective view of a first embodiment of the
claimed design;

FIG. 2 is a bottom perspective view thereof;

FIG. 3 is a back view thereof;

FIG. 4 is a front view thereof;

FIG. 5 is a top view thereof;

FIG. 6 is a bottom view thereof;

FIG. 7 is a left side view thereof;

FIG. 8 is a right side view thereof;

FIG. 9 is a bottom perspective view of a second embodiment
of the claimed design, the top perspective view being the
same as that shown in FIG. 1, and the top view being the same
as that shown in FIG. 5;

FIG. 10 is a back view thereof;

FIG. 11 is a front view thereof;

FIG. 12 is a bottom view thereof;

FIG. 13 is a left side view thereof; and,

FIG. 14 is a right side view thereof.

The ornamental design which is claimed is shown in solid
lines in the drawings. The broken lines in the drawings are for
illustrative purposes only and form no part of the claimed
design. Broken lines formed by equal length dashes show
unclaimed portions of the design. Broken lines formed of
unequal length dashes (i.e., dash-dot) show boundaries
between claimed and unclaimed portions of the design.

While the accompanying drawings illustrate one or more
exemplary embodiments, it should be understood that accord-
ing to other exemplary embodiments that should be consid-
ered to be within the possession of the inventors of the present
application at the time this application is being filed, and to
have been within the possession of the inventors of the prior-
ity application at the time the priority application was being
filed, it is and was contemplated that any illustrated solid lines
(or portions thereof) may be converted to broken lines and
that any illustrated broken lines (or portions thereof) may be
converted to solid lines so as to claim or disclaim portions,
components, or sub-components of the designs shown. It is
and was further contemplated that shading may be added or
removed to claim or disclaim the corresponding surfaces.
